ROOF GLAZING STRUCTURE

Hans Brigggen, Vienna, Austria

Application November 8, 1935, Serial No. 48,914
In Austria November 16, 1934

13 Claims. (Cl. 108—16)

This invention relates to a roof glazing or skylight structure in which the use of putty or any cement is dispensed with. One object of this invention is to provide a roof glazing or skylight structure in which the overlapping edges of adjacent glass plates have sufficient freedom of relative movement for enabling them to automatically adjust themselves in accordance with any variations of strains and dilatations and contractions 5 to which these plates may be subjected, the roof glazing structure or skylight structure being nevertheless maintained perfectly water tight. Another object of the invention is to provide a roof glazing or skylight structure in which there 10 are no connecting elements, such as screws, rivets, wedges or the like on the outer side of said structure.

With these objects in view according to this invention the overlapping edges of the glass plates 20 are supported on curved and preferably elastic surfaces of superimposed supporting elements, the relative position of the glass plates and said supporting elements being maintained by springs engaging each other and one of said supporting elements, one of said springs being secured to said supporting element.

The invention is also applicable when a second glazing is arranged inside an outer glazing, the two glazings having in common the supporting 30 elements.

The invention is illustrated in the accompanying sheet of drawing in which Fig. 1 is a vertical section of a preferred form of a single glazing according to the present invention, while Fig. 2 is 35 a similar view of a preferred form of a double glazing according to the present invention.

The overlapping glass plates 13, 14 are preferably provided at their edges with flanges 15 perpendicular to the body of said plates and serving 40 for leading off rain water or condensed water to the eaves drops. The lower glass plate 13 rests on the supporting surface 3 mounted on a supporting element 1 which may consist of a glazing rod, the parts being so shaped that the glass plate 45 may rock on the supporting surface without interfering with its intimate contact with said supporting surface 3. A bar shaped cushion 16 is interposed between the edges of the glass plates 13, 14 overlapping each other, this cushion bar 50 being located as nearly as possible vertically to the supporting element 1. The plane bottom side of the cushion 16 rests on the lower glass plate 13, while the top side of the cushion 16 serves as a bearing for the upper glass plate 14 and is suitably 55 curved for enabling the glass plate 14 to adjust

itself relatively to the glass plate 13 by rocking on the top side of the cushion 13 or by sliding over the same.

The cushion 16 and the supporting surface 3 are preferably made of an elastic material for instance of a hemp core with a lead covering as usual in the art or of a material not hitherto used for the purpose, consisting of some fibrous material such as hemp impregnated with a bituminous emulsion throughout or on its surface 10 only. This latter material is superficially adhesive, so that the glass plates adhere thereto thereby improving the operation of the structure.

The cushion 16 and the supporting surface 3 and the glass plates 13, 14 are held in their proper 15 relative position by springs 12 and 17 of which the spring 12 is held in position on the body of the supporting element or glazing rod 1 by screws, wedges or the like. The spring 12 passes round the flange 15 of the lower glass plate 13 and its 20 upper end enters between the glass plate 13 and the cushion 16. The end of the spring 12 bearing on the top side of the glass plate 13 is provided with an upwardly directed rib engaging into a corresponding groove in the bottom side 25 of the cushion 16 for holding said cushion in position above the supporting element 1. The other spring 17 engages also below the cushion 16 and is also provided with an upwardly projecting rib 30 engaging into the same groove of the bottom side of the cushion as the similar rib of the spring 12 as above explained. The spring 17 passes round the free edge of the upper glass plate 14 and holds this plate 14 against the cushion 16.

Instead of providing the springs 12 and 17 as just described, the glass plates can be directly connected to the supporting elements by cementing.

In the construction shown in Fig. 2 the head 40 of the supporting element 1 is provided with a groove 2 receiving the supporting surface 3. Thereby the supporting surface 3 is more reliably locked against lateral shifting relatively to the supporting element without, however, interfering 45 with the free adjustability of the glass plates relatively to the supporting element 1.

The bottom flange 4 of the glazing rod serving as the supporting element 1 is provided with turned up edges supporting soft cushion strips 50 5, 6 on which rest the glass plates 7, 8 located on opposite sides of the supporting element 1 the edges of which cannot overlap each other, but are in the same level. For preventing accidental movements of the glass plates 7, 8 they are held 55

against the cushioning strips 5, 6 by springs 9, 10 secured to the supporting element 1 by the screw 11 which serves for securing the spring 12 which holds the lower glass plate 13 of the 5 outer glazing layer against the supporting surface 3. The glass plates 7, 8 constitute the inner glazing layer.

The cushioning strips 5, 6 consist preferably of the same elastic material as the cushion bar and 10 the supporting surfaces on which rest the glass plates constituting the outer glazing layer.

What I claim is:

1. A roof glazing structure comprising two parallel sets of glass plates, the glass plates of 15 one of said sets overlapping the glass plates of the other set, supporting elements for the lower set of glass plates, cushions interposed between said glass plates of said sets and supporting the glass plates of said upper set of glass plates, sup- 20 porting surfaces mounted on the supporting elements of the lower set of glass plates, means for preventing the said cushions and supporting surfaces from being shifted laterally, said cush- 25 ions and supporting surfaces having curved tops and the lines of contact between said cushions and the upper set of glass plates and the lines of contact between said supporting surfaces and the glass plates of said lower set being substan- 30 tially in a vertical plane with the central vertical plane of the associated one of said supporting elements, said glass plates being in elastic relation to each other and to said supporting elements.

2. A roof glazing structure comprising two parallel sets of glass plates, the glass plates of 35 one of said sets overlapping the glass plates of the other set, supporting elements for the lower sets of glass plates, cushions interposed between said glass plates of said sets and supporting the glass plates of said upper set of glass plates, sup- 40 porting surfaces mounted on the supporting elements of the lower set of the glass plates, means for preventing the said cushions and supporting surfaces from being shifted laterally, said cush- 45 ions and supporting surfaces having curved tops and the lines of contact between said cushions and the upper set of glass plates and the lines of contact between said supporting surfaces and the glass plates of said lower set being substan- 50 tially in a vertical plane with the central vertical plane of the associated one of said supporting elements, said cushions and said supporting surfaces being elastic.

3. A roof glazing structure comprising two parallel sets of glass plates, the glass plates of 55 one of said sets overlapping the glass plates of the other set, supporting elements for the lower set of glass plates, cushions interposed between said glass plates of said sets and supporting the glass plates of said upper set of glass plates, sup- 60 porting surfaces mounted on the supporting elements of the lower set of glass plates, means for preventing the said cushions and supporting surfaces from being shifted laterally, said 65 cushions and supporting surfaces having curved tops and the lines of contact between said cushions and the upper set of glass plates and the lines of contact between said supporting surfaces and the glass plates of said lower set being substan- 70 tially in a vertical plane with the central vertical plane of the associated one of said supporting elements, said cushions being bar shaped and said supporting surfaces being secured to said supporting elements.

75 4. A roof glazing structure comprising two

parallel sets of glass plates, the glass plates of one of said sets overlapping the glass plates of the other set, supporting elements for the lower set of glass plates, cushions interposed between said glass plates of said sets and supporting the glass plates of said upper set of glass plates, sup- 5 porting surfaces mounted on the supporting elements of the lower set of glass plates, means for preventing the said cushions and supporting surfaces from being shifted laterally, said cush- 10 ions and supporting surfaces having curved tops and the lines of contact between said cushions and the upper set of glass plates and the lines of contact between said supporting surfaces and the glass plates of said lower set being substan- 15 tially in a vertical plane with the central vertical plane of the associated one of said supporting elements, said cushions and supporting surfaces being made of fibrous material impregnated with a bituminous emulsion.

20 5. A roof glazing structure comprising two parallel sets of glass plates, the glass plates of one of said sets overlapping the glass plates of the other set, supporting elements for the lower set of glass plates, cushions interposed between said glass plates of said sets and supporting the glass plates of said upper set of glass plates, sup- 25 porting surfaces mounted on the supporting elements of the lower set of glass plates, means for preventing the said cushions and supporting surfaces from being shifted laterally, said cush- 30 ions and supporting surfaces having curved tops and the lines of contact between said cushions and the upper set of the glass plates and the lines of contact between said supporting surfaces and the glass plates of said lower set being substan- 35 tially in a vertical plane with the central vertical plane of the associated one of said supporting elements, said cushions and supporting surfaces being superficially adhesive whereby the said 40 glass plates adhere to them.

6. A roof glazing structure comprising two parallel sets of glass plates, the glass plates of one of said sets overlapping the glass plates of the other set, supporting elements for the lower set 45 of glass plates, cushions interposed between said glass plates of said sets and supporting the glass plates of said upper set of glass plates, sup- 50 porting surfaces mounted on the supporting elements of the lower set of glass plates, means for preventing the said cushions and supporting surfaces from being shifted laterally, said cushions and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each 60 other and to said supporting elements in combination with springs holding the said glass plates against each other, against said cushions and against said supporting surfaces.

7. A roof glazing structure comprising two parallel sets of glass plates, the glass plates of one of said sets overlapping the glass plates of the other set, supporting elements for the lower sets of glass plates, cushions interposed between said glass plates of said sets and supporting the glass 70 plates of said upper set of glass plates, sup- 75 porting surfaces mounted on the supporting elements of the lower set of glass plates, means for preventing the said cushions and supporting surfaces from being shifted laterally, said cushions 80

- and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each other and to said supporting elements in combination with springs secured to said supporting elements passing round the associated one of said lower set of glass plates and holding the same to said associated supporting elements and engaging into said cushion between the glass plates of said two sets whereby a lateral displacement of said cushions is prevented.
8. A roof glazing structure comprising two parallel sets of glass plates, the glass plates of one of said sets overlapping the glass plates of the other set, supporting elements for the lower set of glass plates, cushions interposed between said glass plates of said sets and supporting the glass plates of said upper set of glass plates, supporting surfaces mounted on the supporting elements of the lower set of glass plates, means for preventing the said cushions and supporting surfaces from being shifted laterally, said cushions and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each other and to said supporting elements, in combination with springs secured to said supporting elements passing round the associated one of the said lower set of glass plates and holding the same to said supporting elements and engaging into said cushions between the glass plates of said two sets, and other springs passing round the edge of the plate of said upper set and engaging both the first named springs and said cushion.
9. A roof glazing structure comprising two parallel sets of glass plates, the glass plates of one of said sets overlapping the glass plates of the other set, supporting elements for the lower set of glass plates, cushions interposed between said glass plates of said sets and supporting the glass plates of said upper set of glass plates, supporting surfaces mounted on the supporting elements of the lower set of the glass plates, means for preventing the said cushions and supporting surfaces from being shifted laterally, said cushions and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each other and to said supporting elements and said supporting surfaces for the lower set of glass plates being mounted in a recess of said supporting element.
10. A roof glazing structure comprising two parallel sets of glass plates, the glass plates of one of said sets overlapping the glass plates of the other set, supporting elements for the lower set of glass plates, cushions interposed between said glass plates of said sets and supporting the glass plates of said upper set of glass plates, supporting surfaces mounted on the supporting elements of the lower set of the glass plates, means for preventing the said cushions and supporting surfaces from being shifted laterally, said cushions and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each other and to said supporting elements, in combination with a further set of glass plates arranged on the inside of the first named two sets of glass plates, the adjacent edges of neighbouring glass plates of said further set being located on opposite sides of the said supporting element having a bottom flange with upturned edges supporting the last named glass plates.
11. A roof glazing structure comprising two parallel sets of glass plates, the glass plates of one of said sets overlapping the glass plates of the other set, supporting elements for the lower set of glass plates, cushions interposed between said glass plates of said sets and supporting the glass plates of said upper set of glass plates, supporting surfaces mounted on the supporting elements of the lower set of glass plates, means for preventing the said cushions and supporting surfaces from being shifted laterally, said cushions and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each other and to said supporting elements in combination with a further set of glass plates arranged on the inside of the first named two sets of glass plates, the adjacent edges of neighbouring glass plates of said further set being located on opposite sides of said supporting elements having a bottom flange with upturned edges carrying cushioning strips supporting the last named glass plates.
12. A roof glazing structure comprising two parallel sets of glass plates, the glass plates of one of said sets overlapping the glass plates of the other set, supporting elements for the lower set of glass plates, cushions interposed between said glass plates of said sets and supporting the glass plates of said upper set of glass plates, supporting surfaces mounted on the supporting elements of the lower set of glass plates, means for preventing the said cushions and supporting surfaces from being shifted laterally, said cushions and supporting surfaces having curved tops and the lines of contact between said cushions and the upper set of glass plates and the lines of contact between said supporting surfaces and the glass plates of said lower set being substantially in a vertical plane with the central vertical plane of the associated one of said supporting elements, said glass plates being in elastic relation to each other and to said supporting elements in combination with a further set of glass plates arranged on the inside of the first named two sets of glass plates, the adjacent edges of neighbouring glass plates of said further set being located on opposite sides of said supporting elements having a bottom flange with upturned edges supporting the last named glass plates.

edges carrying cushioning strips supporting the last named glass plates and in further combination with springs holding the last named glass plates against said cushioning strips.

- 5 13. A roof glazing structure comprising two parallel sets of glass plates, the glass plates of one of said sets overlapping the glass plates of the other set, supporting elements for the lower set of glass plates, cushions interposed between 10 said glass plates of said sets and supporting the glass plates of said upper set of glass plates, supporting surfaces mounted on the supporting elements of the lower set of glass plates, means for preventing the said cushions and supporting 15 surfaces from being shifted laterally, said cushions and supporting surfaces having curved tops and the lines of contact between said cushions and the upper set of glass plates and the lines of contact between said supporting surfaces and 20 the glass plates of said lower set being substan-

tially in a vertical plane with the central vertical plane of the associated one of said supporting elements, said glass plates being in elastic relation to each other and to said supporting elements in combination with a further set of 5 glass plates arranged on the inside of the first named two sets of glass plates, the adjacent edges of neighbouring glass plates of said further set being located on opposite sides of said supporting elements having a bottom flange with up- 10 turned edges carrying cushioning strips supporting the last named glass plates and in further combination with further springs attached to said supporting elements, said further springs holding the last named glass plates against said 15 cushioning strips, said springs being held in position by the same means that hold in position said spring holding down the associated glass plate of the first named two sets of glass plates.

HANS BRIGGEN. 20
